UNITED STATES PATENT OFFICE.

GEORGE T. BROWN, OF WINSTON, NORTH CAROLINA.

DESIGN FOR A PAPER LANTERN-BLANK.

SPECIFICATION forming part of Design No. 27,023, dated May 4, 1897.

Application filed March 15, 1897. Serial No. 627,706. Term of patent 7 years.

To all whom it may concern:

Be it known that I, GEORGE T. BROWN, a citizen of the United States, residing at Winston, in the county of Forsyth and State of North Carolina, have invented and produced a new and original Design for Paper Lantern-Blanks, of which the following is a specification, reference being had to the accompanying drawing, forming part thereof.

10 The figure is a face view or elevation of a paper blank embodying my design.

The leading feature of my design consists in the main portion A, formed of the sections a a' a^2 a^3 of equal length, the sections a and a^2 being provided with openings B B', which 15 may receive suitable transparent coverings, on which may be provided any desired inscriptions.

The sections a , a' , and a^3 are provided, respectively, with extensions C, C', and C³ at 20 one end and with extensions D, D', and D³ at their other ends, and at the side of section a I provide a narrow wing E.

The extensions D' and D³ are shorter than the extensions C' and C³, and in the extension 25 D, I form centrally an opening d.

What I claim is—

The design for a lantern-blank herein described and shown.

GEORGE T. BROWN.
